UNITED STATES PATENT OFFICE.

CHARLES SHUH, OF NEWBERRY, INDIANA.

FENCE-POST.

SPECIFICATION forming part of Letters Patent No. 590,914, dated September 28, 1897.

Application filed July 1, 1897. Serial No. 643,086. (No model.)

To all whom it may concern:

Be it known that I, CHARLES SHUH, of Newberry, in the county of Greene and State of Indiana, have invented a new and Improved 5 Fence-Post, of which the following is a full, clear, and exact description.

The object of the invention is to provide a new and improved fence-post which is simple and durable in construction and arranged to 10 be securely held in the ground and also arranged to prevent moisture from corroding or otherwise injuring the metallic foot of the standard.

The invention consists principally of a metallic standard having a twisted foot, a base 15 formed of clay and provided with a central aperture for the reception of the twisted foot of the standard, and a cement for securing the said foot in the base.

20 The invention also consists of certain parts and details and combinations of the same, as will be fully described hereinafter and then pointed out in the claims.

Reference is to be had to the accompanying 25 drawings, forming a part of this specification, in which similar characters of reference indicate corresponding parts in all the figures.

Figure 1 is a sectional side elevation of the improvement on the line 1 1 of Fig. 2. Fig. 30 2 is a plan view of the same, and Fig. 3 is an inverted plan view of the standard.

The base A, made of clay or like material and properly burned, is formed on its outside 35 with longitudinally-extending recesses A', so that when the base is placed in the ground the latter can be readily packed into the said recesses to hold the base securely in place.

The base A is provided with a central polygonal aperture into which extends the foot B 40 of a metallic standard provided with a flange B', resting on the top of the base A to close the upper end thereof, the said flange carrying an extension B², to which the post is secured in the usual manner. The flange B'

is provided with depending arms B³, clasping 45 the outer faces of the base A at the upper ends of the recesses A', to securely and properly hold the foot B and the post in place on the base A. The foot B is twisted, as plainly indicated in Figs. 1 and 3, and the aperture 50 in the base is filled with a plastic binding material, such as cement C, to securely fasten the foot in place in the base A when the said material dries and hardens. Now it will be seen that by having the foot twisted it is 55 securely fastened in position by the hardened cement, so that the post is not liable to become loose, and as the foot is entirely surrounded by the cement no moisture whatever can get to the foot and corrode the same, as 60 is so frequently the case in metallic fence-posts as heretofore constructed. The cement extends to the top of the base, so that the flange B' rests partly on the base and on the cement to exclude moisture at this point. 65

Having thus fully described my invention, I claim as new and desire to secure by Letters Patent—

1. A fence-post comprising a tubular base formed with recesses on the outside, and a 70 standard having a twisted foot extending into the said base, the standard being provided with a flange having arms engaging the face of the base at the said recesses, to securely hold the standard in place on the said base, 75 substantially as shown and described.

2. A fence-post comprising a standard having a twisted foot and a flange at the upper end of the said foot, a base formed with a central aperture for the passage of the said 80 foot, and a plastic material for filling the opening in the said base and for engaging the twists of the said foot, to lock the foot in place, substantially as shown and described.

CHARLES SHUH.
